Primary Examiner — April Rivas*Assistant Examiner* — Jillian Mazzola(74) *Attorney, Agent, or Firm* — The Roy Gross Law Firm, LLC; Roy Gross(57) **CLAIM**

The ornamental design for a basket, as shown and described.

DESCRIPTION

FIG. 1 is a first perspective view showing the new design of a basket in an open configuration;

FIG. 2 is a second perspective view of the basket depicted in FIG. 1;

FIG. 3 is a front view of the basket depicted in FIG. 1; FIG. 4 is a bottom view of the basket depicted in FIG. 1; FIG. 5 is a third perspective view of the basket depicted in FIG. 1;

FIG. 6 is a left side view of the basket depicted in FIG. 1, where the right side view is a mirror image of FIG. 6; and, FIG. 7 is top view of the basket depicted in FIG. 1. Those portions of the design depicted in dashed lines are not considered part of the inventive design.
